UNITED STATES PATENT OFFICE.

GUSTAV A. BRACHHAUSEN, OF HOBOKEN, ASSIGNOR TO THE REGINA MUSIC BOX COMPANY, OF JERSEY CITY, NEW JERSEY.

SPRING-MOTOR.

SPECIFICATION forming part of Letters Patent No. 547,839, dated October 15, 1895.

Application filed January 19, 1895. Serial No. 536,434. (No model.)

To all whom it may concern:

Be it known that I, GUSTAV A. BRACHHAUSEN, a subject of the Emperor of Germany, residing at Hoboken, Hudson county, State of New Jersey, have invented certain new and useful Improvements in Spring-Motors, of which the following is a specification.

My invention relates to spring-motors, and the object thereof is to produce a strong, cheap, and reliable motor having but few parts, which are so arranged that the spring-drum with the spring contained therein can be readily removed and replaced without dismounting or disorganizing any of the various other parts of the motor.

To this end my invention consists in the novel construction and arrangement of parts hereinafter described and claimed. The advantage of such a construction will be obvious when it is remembered how often the main-spring is broken and the other parts of the motor remain intact. In music-boxes and the like as heretofore constructed it was necessary when the mainspring was broken to send the entire box or the movement thereof to the factory in order to have a new spring put in, it being often necessary in such constructions to dismount the various parts of the entire structure in order to accomplish this end. This entailed long delays and great expense in replacing the spring and shipping parts of the motor, which by my invention is rendered unnecessary.

In the drawings forming part hereof, Figure 1 is an end view of a spring-motor constructed in accordance with my invention. Fig. 2 is a transverse sectional view of the same on the line 2 2 of Fig. 1. Fig. 3 is a detail view with parts broken away of a portion of my improved motor, which is hereinafter described.

The drum A for the mainspring *a* is provided with or rigidly connected to a gear-wheel *b*, which meshes with a pinion *c*, rigidly connected with a gear *d*, which gear *d* operates a suitable governor *e* through a pinion *f*, gear *g*, and worm *h*. The gear *b* of the drum A also meshes with a pinion *i*, which is integral with the driving-wheel *k* of the motor. This driving-wheel *k* is removably and loosely mounted upon a pintle *y*, supported by the

framing C, which extends from the bed-plate D. The outer end of the mainspring *a* is connected to the drum A, as shown at *x*, the inner end of the spring being adapted to be connected with one section *l* of a two-part clutch, as shown at *z*. The other section *m* of the clutch is formed integral with or connected to an internally-toothed gear B, which is operated by a pinion *n* on the winding-post *o* of the motor and is prevented from backward movement by a noiseless pawl X, as will be hereinafter more fully described. A spindle *p* is supported by the framing C and is projected through and forms the pivot for the internally-toothed gear B, the two-part clutch, and the spring-drum, all of which are held in place thereon by a suitable retaining-sleeve *q*, having a set-screw *r*. The noiseless pawl X, which is suitably pivoted to the framing C, is controlled by a friction-plate *s*, the annular ring *t* of which is adapted to fit in the annular recess *u* of the hub of the internally-toothed gear B and be held in place therein by a superposed plate *v*, the projections *w* on the annular ring of this friction-plate tending to hold the same in frictional contact with the hub of the gear B and rotate the plate therewith. The outer end of the friction-plate *s* is provided with a slot in which a pin on the pawl X enters. By this arrangement it will be observed that a rotation of the gear-wheel B in the direction of the arrow will cause the friction-plate *s* to be rotated therewith by its frictional contact and to lift the pawl X out of engagement with the teeth thereof. However, the slightest movement of the gear-wheel B in the opposite direction will cause the pawl X to be forced into engagement with the teeth of the gear by the friction-plate.

Having described the construction of my improved motor, I will now proceed to describe the operation thereof. A suitable key or crank is attached to the key-post *o* and operated to turn the pinion *n* in the direction of the arrow, which pinion will cause the gear B to be rotated, thus carrying the pawl out of engagement with the teeth thereof. The rotation of the gear B causes the section *m* of the two-part clutch to be rotated with it and in this manner transmit movement to the clutch-section *l* to wind the spring. In

case the mainspring should become damaged or broken, it is merely necessary to remove the retaining-sleeve *q*, when the drum, with clutch-section *l*, attached to the spring *a* therein, can be removed, and the damaged spring replaced by a new one. The drum can then be replaced upon the spindle, the retaining-sleeve secured in place, and the motor is again in condition for use.

10 While I have described with some particularity the various parts of the construction as illustrated in the drawings, I would have it understood that such construction illustrates but one form of my invention and that 15 various modifications may be made therein without departing from the spirit of my invention. For instance, instead of using one spring-drum, &c., a number of such drums and their connecting mechanism might be employed upon the same spindle where great power is desired.

Having described my invention, what I claim is—

1. In a motor, the combination of a spring drum, a spring and spindle for said drum, a two-part clutch both members of which are loosely mounted on said spindle, one member of said clutch being connected directly to one end of the spring and the other member of 25 said clutch being connected with means for winding it, substantially as described.
2. In a motor, the combination of a revolving spring drum, a spring and spindle for said drum, a two-part clutch both members of 30 which are loosely mounted on said spindle,

one member of said clutch being formed integral with a suitable gear and the other member being connected directly to the spring, and means for operating said gear, substantially as described.

3. In a motor, the combination of a spring drum, a gear-wheel thereon, a driving wheel operated thereby, a governor, a train of gear connecting with the governor, said train being also operated by the gear on said spring 45 drum, a gear-wheel *B*, having clutch section formed integral therewith, and a second clutch section connected directly to the spring in the drum and adapted to engage with the clutch section on the wheel *B* when the drum is in 50 place, and means connected with said wheel *B* for winding the spring, a train of gear driven therefrom, substantially as described.

4. In a motor, the combination of gear-wheel *B*, a friction plate controlled by the movement of said gear wheel *B*, a pawl mounted upon a fixed part of the motor and connecting with said friction-plate, whereby a movement of the gear-wheel in one direction will cause the pawl to engage the teeth of the gear-wheel, 55 and prevent further movement thereof, and a movement of the gear-wheel in the opposite direction will cause the pawl to be disengaged therefrom, substantially as described.

The foregoing specification of my invention 60 signed by me this 15th day of January, 1895.

GUSTAV A. BRACHHAUSEN.
